Primary Examiner — Patricia A Palasik*(74) Attorney, Agent, or Firm* — Middleton Reutlinger(57) **CLAIM**

The ornamental design for a robotic motor unit, as shown and described.

DESCRIPTION

FIG. 1 is a first side view of an embodiment of a robotic motor unit;

FIG. 2 is a second side view of the robotic motor unit of FIG. 1;

FIG. 3 is a third side view of the robotic motor unit of FIG. 1;

FIG. 4 is an upper perspective view of the robotic motor unit of FIG. 1;

FIG. 5 is a top view of the robotic motor unit of FIG. 1; and, FIG. 6 is a lower perspective view of the robotic motor unit of FIG. 1.

The broken line disclosure represents unclaimed portions of the robotic motor unit in which the design is embodied.
